A. R. KAHL,
TELEPHONE TRANSMITTER,
APPLICATION FILED MAR. 20, 1916.

1,334,541.

Patented Mar. 23, 1920.

UNITED STATES PATENT OFFICE.

ARTHUR ROBERT KAHL, OF WITHTINGTON, ENGLAND.

TELEPHONE-TRANSMITTER.

1,334,541.

Specification of Letters Patent. Patented Mar. 23, 1920.

Application filed March 20, 1916. Serial No. 85,246.

To all whom it may concern:

Be it known that I, ARTHUR R. KAHL, a citizen of the United States, residing at 59 Burton road, Withington, Manchester, England, have invented certain new and useful Improvements in Telephone-Transmitters, of which the following is a specification.

My invention relates to an improved form of telephone transmitter in which I provide an improved mounting means for the variable resistance element so that the delicate diaphragm of said element is relieved from undue strains in the assembling and adjusting operation.

My invention consists essentially in providing the variable resistance element with a projecting stud or arm by which the element is rigidly supported from the framework or bridge of the transmitter, this being accomplished by mounting on the bridge a bushing rigidly secured to but insulated from the bridge, which loosely receives said stud, and when the parts of the transmitter have been assembled, securing the stud and bushing together by means of material between them, such as solder, cement, etc., so that the stud and bushing are united and in effect become a rigid structure held without clamping action upon said stud. In the past it has been common to secure the variable resistance element to the bridge by means of a clamping screw, and this has been found to place considerable distortion in the delicate diaphragm of the variable resistance element so that its free operation was subsequently interfered with.

My invention will be better understood by reference to the drawings, which are as follows:

Figure 1 is a longitudinal sectional view through a completely assembled transmitter, some of the parts being shown in elevation for clearness;

Fig. 2 shows in longitudinal central sectional view the variable resistance element, together with its mounting means; and

Fig. 3 is a back view to a reduced scale of the complete transmitter with the outer protecting back shell removed.

Similar numerals refer to similar parts throughout the several views.

As shown in Fig. 1, the transmitter consists of a front plate 10 in which the usual mouthpiece 11 is mounted, and upon the inner surface of which the edge of the main diaphragm 12 rests. A thin ring of insu-

lating material 13, such, for example, as mica or empire cloth, is disposed between the diaphragm and the front plate 10 to somewhat deaden the metallic vibrations that might otherwise be readily set up in the diaphragm. The front plate 10 has secured to its rear surface a bridge 14, bent rearwardly at its middle portion, to mount the rear end of the variable resistance element 15, the front end of which is secured by clamp nuts, as indicated, to the central portion of the main diaphragm 12.

As seen more clearly in Fig. 2, the bridge 14 has mounted at its middle portion a first bushing 16 insulated from said bridge as shown, and held in place by a nut 17. The bushing 16 is provided with a bore sufficiently large to receive within it a second bushing 18, which may be moved longitudinally in said bore to adjust it to the proper position, and when in said position it is securely held in place in the bushing 16 by means of the set screw 19 extending through the enlarged end or head of the bushing 16. The variable resistance element 15 is of a construction similar to that found in telephone transmitters, and consists of a cup portion for receiving the back electrode 20, which is held in place by a clamping ring 21 screwed into the cup portion. The front of the element is closed by a thin mica diaphragm 22 held in place by an inwardly flanged ring 23 screwed on the outer end of the threaded ring 21. The mica diaphragm 22 is clamped between the disk 24 carried by the screw stud 25, and a disk 26 held in place by a nut 27. Both disks are preferably of metal and the inner disk has secured to it the front electrode 28. A second nut 29 on the screw stud 25 clamps the main diaphragm 12 against the nut 27, a connector 30 being interposed between the diaphragm and the nut 27. The central portion of the rear wall of the cup is provided with a boss, into which is screwed the threaded end of a stud or arm 31, which stud is preferably of somewhat smaller diameter than the bore of the bushing 18. A second connector 32 is clamped under the nut 17 so that electrical connection may readily be made with the back electrode.

In assembling the transmitter the resistance element 15 is secured to the main diaphragm by means of the nuts referred to with the connector 30 in place and placed in proper position against the front plate 10,

the insulating ring 13 being interposed as described. The bridge 14 with the stud 16 and connector 32 rigidly secured thereto are then put in position against the projecting lugs 10^a of the front plate and screwed thereto as indicated. The resistance element and main diaphragm are then adjusted until the stud 31 is centered in the bushing 16, and the sleeve 18 is put in place so that its outer 10 end is somewhat forward of the rear end of the stud 31, in which position the bushing 18 is securely clamped by the screw 19. The bushing 18 and the outer end of the stud 31 are preferably tinned before being assembled. The dampening springs 33 are then screwed in place, their inner ends resting against a disk 34 of insulating material, such as empire cloth, which was placed back 15 of the main diaphragm in its assembly with the resistance element. The outer end of the connector 30 is then screwed to the binding post 35 carried by and insulated from the bridge, the other connector 32 having previously been secured to the other binding post 36 similarly mounted upon the bridge. With the dampening springs properly adjusted so that the stud 31 is free in the bushing 18 and so that the proper tension is exerted upon the main diaphragm 12, the 20 bushing 18 and the stud 31 are secured together by running melted solder around or between the ends of the bushing and the stud so as to unite these parts together to form a rigid structure, without, however, 25 exerting any strain or cramping effect upon the stud, as would be the case if a clamping screw were used against said stud. The inclosing shell or casing 37 is then put in place and secured to the front plate 10 by suitable 30 screws in a manner well known in the art to inclose and protect the parts of the transmitter. While I find it convenient to employ solder for securing the stud 31 and bushing 18 together, it will be understood 35 that other materials may be employed for this purpose, such, for example as brazing spelter of any kind or any suitable cement which has sufficient fluidity either as the result of heating or the presence of a proper 40 solvent to flow into the space between the bushing and the stud. Furthermore, the stud and bushing may be secured or united together to form a rigid structure in other ways, as for example, by electric welding, 45 in which case the filling material may fully or in part be furnished by the stud or bushing or both.

As a result of the improved construction described, it will be observed that the resistance element is rigidly secured to the bridge of the transmitter without bringing any strain of any kind to bear upon the resistance element, and that therefore the delicate diaphragm of the resistance element is free 50 to respond properly to the slightest vibra-

tions of the main diaphragm of the transmitter. It will be understood that this manner of mounting the variable resistance element may be used in connection with any style of transmitter in which a so-called "solid back" construction is employed that is to say, in connection with any variable resistance element which is rigidly supported from its rear wall, or in fact any type of transmitter in which the variable resistance element may be supported wholly or in part by a stud extending rearwardly from said element. I do not limit myself, therefore, in the claims to any particular transmitter construction, but desire to claim broadly any transmitter construction in which the mounting of the variable resistance element is effected without subjecting the resistance element to cramping or binding, while at the same time affording a rigid and positive support for said stud. 70 75 80 85

The carbon granules commonly employed in telephone transmitters are not shown in the drawings, as their use in variable resistance elements is well known in the art and they require no special illustration or description. 90

What I claim is:

1. In a telephone transmitter, the combination of a mounting plate, a diaphragm, a bridge secured to said plate, a variable resistance element secured on one side to said diaphragm and having a stud projecting from its other side, a bushing carried by and insulated from said bridge for receiving said stud, and means for securing said stud and bushing together without displacement of said stud in said bushing. 95 100

2. In a telephone transmitter, the combination of a mounting plate, a diaphragm, a bridge secured to said plate, a variable resistance element secured on one side to said diaphragm and having a stud projecting from its other side, a first bushing rigidly secured to said bridge and insulated therefrom and provided with a clamping screw, and a second bushing mounted in said first bushing and held therein by said screw and having a bore for receiving said stud, said second bushing and said stud being secured together by material around said stud and within said second bushing uniting them into a rigid structure. 105 110 115

3. In a telephone transmitter, the combination of a mounting plate, a diaphragm, a bridge secured to said plate, a variable resistance element secured on one side to said diaphragm and having a stud projecting from its other side, and a bushing carried by and insulated from said bridge for receiving said stud, said bushing and said stud being attached to each other to form a rigid structure without displacement of said stud in said bushing. 120 125

4. In a telephone transmitter, the combi- 130

- nation of a mounting plate, a diaphragm, a bridge secured to said plate, a variable resistance element secured on one side to said diaphragm and having a stud projecting 5 from its other side, a bushing carried by and insulated from said bridge for receiving said stud, and material between said stud and said bushing attaching them together.
5. In a telephone transmitter, the combination of a mounting plate, a diaphragm, a bridge secured to said plate, a variable resistance element secured on one side to said diaphragm and having a stud projecting from its other side, a bushing carried by and 10 insulated from said bridge for receiving said stud, and material such as solder or cement between said bushing and said stud connecting them to form a rigid structure.
10. In a telephone transmitter, the combination of a mounting plate, a diaphragm, a bridge secured to said plate, a variable resistance element secured on one side to said diaphragm and having a stud projecting from its other side, a first bushing rigidly 15 secured to said bridge and insulated therefrom and provided with a clamping screw, a second bushing mounted in said first bushing and held therein by said screw and having a bore for receiving said stud, and material such as solder or cement 20 between said bushing and said stud connecting them to form a rigid structure.
15. In a mounting for the variable resistance element of a telephone transmitter, the combination of a stud projecting from a variable resistance element, a rigidly supported bushing, and material between said stud and said bushing attaching them together.
20. In a mounting for the variable resistance element of a telephone transmitter, the combination of a stud projecting from a variable resistance element, and a rigidly supported bushing, said bushing and said stud 25 being attached to each other to form a rigid structure without displacement of said stud in said bushing.
25. In a mounting for the variable resistance element of a telephone transmitter, the combination of a stud projecting from a variable resistance element, a bridge, a first bushing rigidly secured to and insulated from said bridge and having a set screw extending through it, and a second bushing carried within said first bushing and held in place around said stud by said set screw, 30 said second bushing and said stud being united to form a rigid structure.
30. In a mounting for the variable resistance element of a telephone transmitter, the combination of a stud projecting from a variable resistance element, a bridge, a first bushing rigidly secured to and insulated from said bridge and having a set screw extending through it, a second bushing carried within said first bushing and held in place around said stud by said set screw, and material such as solder or cement between 35 said second bushing and said stud, connecting them to form a rigid structure.
35. In a telephone transmitter, the combination of a front plate, two supporting members comprising a main diaphragm and a bridge supported by said front plate, a variable resistance element between said supporting members and having oppositely extending studs for connection to said members, a clamping device for securing one of said studs to its supporting member, the other stud entering a free clearance opening therefor in the other supporting member, and a solder connection between the last mentioned stud and its supporting member.
40. In witness whereof I hereunto subscribe my name this 22nd day of February, A. D. 1916.

ARTHUR ROBERT KAHL.
